UNITED STATES PATENT OFFICE

ALFRED C. FLOTHOW, OF MAYWOOD, ILLINOIS, ASSIGNOR TO EVERHOT MANUFACTURING COMPANY, OF MAYWOOD, ILLINOIS, A CORPORATION OF ILLINOIS

BRANDING AND INKING DEVICE

Application filed January 30, 1932. Serial No. 589,801.

The invention relates to devices suitable for branding and marking with ink and more particularly it relates to inking devices providing means for drying the ink as it is applied.

An object of the invention is to provide an improved combination branding and inking device of the kind described.

Another object of the invention is the provision of an improved inking device providing raised characters and means to heat and dry ink applied to such characters in combination with an improved ink pad mounted in cooperative relation with said device.

15 A further object is the provision of a novel inking device in combination with a pad movable into and out of cooperative relation with the device.

A still further object of the invention is 20 the provision of a device of the kind described providing improved means for applying ink to raised characters and to heat such characters to dry the ink as it penetrates the surface to be marked in such manner as to be permanently retained on such surface.

A further object of the invention is the provision of novel means for mounting a pad on a device of the kind described whereby 30 the type or raised characters to be heated are uniformly inked in a relatively short time and thereby enables the ink of all the characters to be uniformly heated and applied to the surface to be branded under uniform conditions tending to prevent smearing of such surfaces.

A still further object of the present invention is to improve devices of the character disclosed in sundry details hereinafter described and particularly pointed out in the claims.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

Fig. 1 is an elevational view of a branding device illustrating one embodiment of the invention;

Fig. 2 is an end view of the device shown in Fig. 1; and

Fig. 3 is a sectional view along the line 3-3 of Fig. 1.

Referring now more particularly to the drawing, the numerals 10, 11 and 12 respectively designate a heating element, a handle, and a member connecting the heating element and handle.

The heating element 10 includes a cylindrical member 13 having an axial bore 14 extending substantially its full length. A tubular member 15, threaded into the bore 14 substantially its full length, has its inner end closed by a plate 16. The plate 16 is fastened by bending inwardly the relatively thin end portion of the tubular member 15. The member 15 has a tubular lining of cement 17 in which a resistance coil 18 is embedded.

The tubular member 15 projects a substantial distance from the cylindrical member 13 and is connected with the offset end of the handle 11 by a spiral member 24 which gives rigidity to the device and provides a connection between the heating element 10 and the handle 11 enabling the parts to be easily assembled. The connecting member 12 also includes a plurality of axially aligned porcelain members numbered 20, 21 and 22 respectively. The member 20 is mounted in the tubular member 15 and is provided with an offset portion permitting it to extend the full length of and closely fit the cement linings 17. The member 20 has a pair of longitudinally extending apertures 38 and 39 which are in alignment with corresponding apertures, not shown, in the members 21 and 22. The adjacent ends of the members 20, 21 and 22 cooperate in any suitable manner. In the

device shown this is accomplished by providing telescoping offset end portions for the adjacent ends of the members. The spiral member 24 is rigid and effectively holds the members in the positions shown. A conductor 19

extends through an axial aperture 40 in the handle 11 and continues through the apertures 38 and 39 in the porcelain members 20, 21 and 22, where they terminate in a resistance coil 18 which is insulated from the tubular member 15 by the cement lining 17. The exposed portions of the conductor 19 are insulated and are provided with a spring cover 23 adjacent the handle 11, to prevent undue strain and bending of the conductor when the device is in use. The conductors 19 are connected with a source of electrical energy and are provided with a switch in the usual manner. Neither the switch nor the source of electrical energy are shown since they are well known in the art and are not considered as forming any portion of the invention.

The cylindrical member 13 is quickly heated by energizing the coil 18. A stem 25, shown as integrally formed and in axial alignment with the cylindrical member 13, provides a mounting for a rotatable disc 26. The disc 26 is provided with one or more type 27, adapted when heated to provide characters on a surface to be branded. The disc 26 is so positioned relative to the cylindrical member 13 that it is heated by the latter when the resistance coil 17 is energized.

The stem 25 also provides a mounting for a circular rotatable ink pad 34. For this purpose an arm 28 is mounted on the end of the stem 25 and held in position by a screw bolt 31, a metal washer 29 and a gasket 30 of heat insulating material.

The outer end of the arm 28 is bifurcated to provide a mounting for an arm 32. The arm 32 is pivotally mounted on a bolt 33 extending through the bifurcated portion of the arm 28. A shaft 35 projects from the outer end of the arm 32 to provide a mounting for the cylindrical ink pad 34. In the full line position of the pad 34 as shown in Fig. 2, the type or characters 27 on the disc 26 are in contact with the surface of the pad 34. Rotation of either the disc 26 or of the pad 34 causes the rotation of both with the type contacting with the pad and results in the type being uniformly coated with sufficient ink for application to a surface to be marked.

The pad 34 is held in its full line position by the contact of the free end of a spring plate 36 with the end of the arm 28, the other end of the spring plate being fastened to the arm 32 by a screw 37. The type 27 having been inked by rotation of the pad 34 and the disc 26, the pad is moved to the dotted line position of Fig. 2 where it is remote from the work and is unaffected by the heating of the disc 26. The pad 34 is moved to its dotted line position by swinging it about the pivot 33 and this compels the application of sufficient force to move the spring plate 36 over the corner of the arm 28 to its dotted line position. The length of the plate 36 and its

mounting is such that it holds the pad 34 against movement in both its full line and dotted line positions.

Thus it will be seen that I have provided a novel inking device and pad for supplying ink to the device as needed, the pad having novel mounting means adapting it to be moved into and out of operative engagement with the work.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A portable branding device comprising a handle member, an electrical heating element carried by the handle, said heating element comprising a heat conducting member providing a bore, a resistance coil in said bore, means for energizing said coil, a branding disc rotatably mounted on said heat conducting member, an arm projecting from the device adjacent said branding disc, a pad mounted on the outer end of the arm, said arm having a joint adapting it to be folded to bring said pad into contact with said disc and when extended to move the pad to a substantial distance from the disc.

2. A portable branding device comprising a handle member, an electrical heating element carried by the handle, said heating element comprising a heat conducting member providing a bore in axial alignment with the handle member, a resistance coil in said bore, means for energizing said coil comprising a pair of conductors extending through the handle, a branding disc mounted on said heat conducting member and rotatable about the longitudinal axis of said bore, an arm projecting from the device adjacent said branding disc, a pad mounted on the outer end of said arm, said arm having a joint adapting it to be folded to bring said pad into contact with said disc and when extended to move the pad to a substantial distance from the disc, and spring means adapted to yieldingly hold the arm either in extended or folded position.

3. A portable branding device comprising a handle member, an electrical heating element carried by the handle, said heating element comprising a heat conducting member providing a bore in axial alignment with the handle member, a resistance coil in said bore, means for energizing said coil comprising a pair of conductors extending through the handle, a branding disc mounted on said heat conducting member and rotatable about the longitudinal axis of said bore, an arm projecting from the device adjacent said branding disc, a pad rotatably mounted on the outer

end of the arm, said arm having a joint adapting it to be folded to bring said pad into contact with said disc and when extended to move the pad to a substantial distance from the disc, said pad and disc having their axes of rotation parallel when in contact, and spring means adapted to yieldingly hold the

arm in either extended or said folded position.

In witness whereof, I hereunto subscribed my name this 27th day of January A. D., 1932.

ALFRED C. FLOTHOW.
